US00D607917S

(12) **United States Design Patent**
Darrow

(10) **Patent No.:** **US D607,917 S**
(45) **Date of Patent:** **** Jan. 12, 2010**

(54) **CAMERA SUPPORT**

(75) Inventor: **Richard Darrow**, Denville, NJ (US)

(73) Assignee: **Tocad America, Inc.**, Rockaway, NJ (US)

(**) Term: **14 Years**

(21) Appl. No.: **29/323,882**

(22) Filed: **Sep. 2, 2008**

Related U.S. Application Data

(63) Continuation-in-part of application No. 12/203,092, filed on Sep. 2, 2008, which is a continuation-in-part of application No. 12/119,455, filed on May 12, 2008, which is a continuation-in-part of application No. 12/148,948, filed on Apr. 23, 2008, which is a continuation-in-part of application No. 11/471,545, filed on Apr. 27, 2007.

(57) **CLAIM**

The ornamental design for the camera support, as shown and described.

DESCRIPTION

FIG. 1 is an isometric view of an embodiment of a camera support showing my new design.

FIG. 2 is a front elevation view of the embodiment.

FIG. 3 is a back elevation view of the embodiment.

FIG. 4 is a left side elevation view of the embodiment.

FIG. 5 is a right side elevation view of the embodiment.

FIG. 6 is a top plan view of the embodiment; and,

FIG. 7 is a bottom plan view of the embodiment.

The broken line showing of portions of the camera support is for the purpose of illustrating the camera support and forms no part of the claimed design.

1 Claim, 7 Drawing Sheets
